BED COVERING

Filed Nov. 24, 1930

UNITED STATES PATENT OFFICE

ELVIRA STARZ SMITH, OF NEWARK, NEW JERSEY

BED COVERING

Application filed November 24, 1930. Serial No. 497,622.

This invention relates, generally, to bed covering; and the invention has reference, more particularly, to a novel form of bed covering or bed case particularly adapted for use on the beds of infants, children and patients and is designed to remain in desired fixed position upon the bed, the said novel bed covering acting to retain any additional bed covering or clothing in desired position on the bed or crib.

As is well known, infants, children and sick persons and even others are more or less restless in their sleep so that the bed clothing or covering becomes displaced and upset, causing the person covered thereby to become unduly chilled, which is apt to lead to colds or other illnesses.

The principal object of the present invention is to provide a novel bed covering or bed case which is so constructed and arranged as to remain in desired fixed position upon a bed and in covering relation to the person using the same, regardless of the restlessness of such person, the said bed covering or case also serving to retain any additional bed clothing used in desired position upon the bed.

Another object of the present invention lies in the provision of a novel bed case which not only overlies the person using the bed, but which also extends completely under the bed mattress, thereby utilizing the weight of the person together with that of the mattress and any additional bed clothing to retain the bed case and such additional clothing in desired fixed position upon the bed, the frictional resistance between the bed case and the bed spring serving to prevent relative movement of the bed case and the spring, which relative movement may be positively prevented, if desired, by the use of fastening means adapted to positively tie the bed case in fixed position upon the bed spring.

Another object of the present invention is to provide a novel bed covering or bed case having an upper or cover portion which is adapted to be readily parted or opened down the middle, as by the use of hookless fastening means, to thereby enable the easy and quick removal of the person from the bed

when desired, or to allow access to the mattress and sheeting thereof as for the purpose of straightening out such sheeting or for inserting or removing the mattress and/or sheeting from the bed case or for airing the same.

A fourth object of the present invention lies in the provision of a novel bed covering or bed case of the above character which is open at the bottom as well as at the top, thereby enabling ready access to the interior thereof both at the bottom and at the top of the bed and permitting ready adjustment of the mattress or sheeting within the case and easy access to the feet of the bed user, as for the purpose of applying hot water bags thereto, the said open ended case being easily laundered and retained in a sanitary condition.

A fifth object of the present invention is to provide a novel bed covering or bed case of the above character having an upper or cover portion provided with a flap at the bottom end thereof, which flap is adapted to be readily tucked around the bottom end of the bed mattress and under the same and between such mattress and that portion of the bed covering or case which extends under and across the mattress.

Still another object of the present invention lies in the provision of a novel bed covering or case which is of extremely simple construction, may be cheaply manufactured, and which is so designed that the user of the bed covering or case will not readily soil the same, thereby reducing laundering expenses to a minimum.

Other objects of this invention, not at this time more particularly enumerated, will be clearly understood from the following detailed description of the same.

The invention is clearly illustrated in the accompanying drawing, in which:—

Fig. 1 is a perspective view with parts broken away showing the novel bed covering or case of this invention as applied to a baby's crib.

Fig. 2 is a plan view of the novel bed covering or case, the cover portion thereof being illustrated as parted or in partly open position.

Fig. 3 is a rear view of the structure shown in Fig. 2.

Fig. 4 is a fragmentary view in side elevation showing the lower portion of a mattress and the novel bed covering or case applied thereto.

Fig. 5 is a sectional view taken along line 5—5 of Fig. 4 and also shows a sheet on the mattress.

Fig. 6 is an enlarged fragmentary view of a portion of the structure of Fig. 5; and

Fig. 7 is a view similar to Fig. 3 of a slightly modified form of construction, the flap portion of the bed case being broken away.

Similar characters of reference are employed in all of the above described views, to indicate corresponding parts.

Referring now to said drawing, the novel bed covering or case of this invention is illustrated as applied to a baby's crib, but it is to be understood that the same is equally applicable to full size beds. The reference numeral 1 designates a crib having a spring 2 and mattress 3 which is equipped with the novel bed covering or bed case 4 of the present invention. This novel bed case or bed covering completely encircles the mattress 3 and any sheeting thereon, thereby utilizing the weight of the mattress and the person on the bed to retain the bed case or covering in desired position.

This novel bed case comprises a tie member or subsheet 5 (see especially Figs. 2 to 5), which subsheet may be made of muslin or other suitable relatively thin and inexpensive material, and is adapted to underlie mattress 3 and to rest directly upon the spring 2 of the bed. The tie member or subsheet 5 is preferably of substantially the same size as the mattress 3, thereby completely underlying the entire mattress and incidentally protecting the mattress from direct contact with the spring 2. The tie member or subsheet 5 is preferably provided with a number of tie strings 6 arranged at the corners thereof for the purpose of tying this subsheet directly to the spring 2, to thereby positively hold or retain the subsheet in fixed position upon the spring 2.

Additional tie strings 6 may be provided intermediate the corner tie strings 6, if desired, as especially illustrated in Figs. 2 and 3, for the purpose of obtaining more complete attachment of the subsheet to the spring. It is to be understood, however, that the use of the tie strings 6 is not absolutely essential owing to the fact that the subsheet passes completely under the mattress 3, and in some instances these tie strings may be omitted altogether.

Spaced side panels or side walls 7 of muslin or other suitable material are disposed at the side edges of the subsheet 5 and cover the greater portion of the sides of the mattress 3.

The side panels or side walls 7 extend from

the bottom or foot end of the subsheet 5 toward the top or head end thereof, but terminate short of the top end of this sheet, as illustrated in the drawing. The lower edge portions of the side panels 7 are sewn to the side edge portions of the subsheet 5, as especially illustrated in Fig. 5. Preferably a decorative binding or trimming ribbon 8 is sewn over the joints between the side panels 7 and the subsheet 5, thereby completely hiding such joints from view.

The side panels extend upwardly from the subsheet 5 at the sides of the mattress 3 and have their upper edge portions sewn to the side edges of an upper or cover portion of the bed case comprising sections 9 and 10. This upper or cover portion of the bed case is adapted to overlie the mattress 3 and extends from the foot or bottom of the bed toward the top or head end thereof to the same extent as the side panels, but terminates short of the top end to leave space for a pillow and to accommodate the head of the bed user. The side panels 7 are of somewhat greater height than the height of the mattress 3 to provide a suitable space above the mattress for receiving the infant or other person using the bed, together with such sheeting and clothing as may be desired.

The sewn juncture of the side panels 7 with the cover portion 9—10 is illustrated as covered by the use of the binding or trimming ribbon 8. The cover portion 9—10 has the bottom or foot end thereof extending beyond the bottom end of the side panels 7 to provide a flap 12 which is adapted to be tucked around the bottom and under the mattress 3, as especially illustrated in Fig. 4, thereby completely enclosing the bottom end of the bed case in use and serving to keep the bed user's feet warm. If desired, the flap 12 may be provided with tie strings (not shown) for retaining the same in place and around the bottom of the mattress.

In the form of the invention illustrated in the figures, wherein the bed covering or case is employed for a crib, the flap 12 is made of the same length as that portion of the subsheet 5 which projects beyond the top or head end of the side panels 7 and the cover portion 9—10. The portion of the flap 12 which is tucked under the mattress 3, lies between this mattress and the subsheet 5, and therefore is firmly and frictionally gripped between these members so that the same will not pull out accidentally while in use. The edges of the flap 12, and the bottom and top edges of the side panels 7 are also preferably provided with binding or trimming ribbon 8.

The sections 9 and 10 forming the cover portion of the bed case of this invention are of substantially the same size and have their meeting edge portions overlapping one another at the center of the case, as especially illustrated in Figs. 2, 5 and 6 of the drawing.

The bottom portion of these sections 9 and 10 forming the flap 12 are directly and permanently sewn together, whereas the portions of these sections which overlie the top of mattress 3 are adapted to be connected or disconnected at will, by the use of a hookless fastener comprising interlockable fastening members 13 attached to the opposite edges of fastener tapes 14 and 15; tape 14 being sewed to the cover section 9, whereas tape 15 is sewed to the cover section 10.

A runner 16 slides on the members 13 and is manipulated by a finger piece 17 in a well known manner to effect attachment of cover sections 9 and 10 or the parting of these sections, whichever is desired. The fastener tape 14 is sewn to the underside of cover section 9 at a point inwardly of the edge of this cover section as shown in Fig. 6, so that the edge portion of this cover section completely overlies the fastening members 13 and tapes 14 and 15, thereby completely hiding the hookless fastener from view when the cover sections are interconnected as illustrated in Fig. 1. Also, the fastener tape 15 is sewn to the upper surface of the cover section 10 at a point inwardly of the edge of this cover section so that the edge portion of this cover portion completely underlies the hookless fastener to prevent the same from contacting with the skin of the bed user.

To render the attachment of the cover sections 9 and 10 at the top or head end of the crib more secure, an auxiliary snap fastener 18 is employed, one-half of this snap fastener being sewed to the cover section 9 and the other half being sewed to the cover section 10. A decorative ribbon or bow 19 overlies that portion of the fastener 18 which is attached to the edge of cover section 9 and this bow serves as an additional covering means for the hookless fastener and especially the finger piece 17 thereof, so that the infant or bed user will be unable to grasp this finger piece or place the same in his mouth.

In use, to apply the novel bed covering or bed case to the mattress, it is merely necessary to place the bed case upon the spring 2 with the tie member 5 resting on the spring and then manipulate finger piece 17 so as to open or part the cover sections 9 and 10, as illustrated in Fig. 2. The tie strings 6 may be tied to the spring in the event that these tie strings are used. The mattress 3 may then be readily slipped in between subsheet or tie member 5 and the cover portions 9-10. Ordinarily, a sheet or sheeting 20 (see Fig. 5) is placed over the mattress 3 and is tucked under at the sides of the same so as to have its marginal side portions gripped between the subsheet or tie member 5 and the bottom of the mattress. The frictional resistance exerted by the bottom of the mattress and by the subsheet 5 upon the tucked under marginal side portions of the sheeting 20, serves

to securely retain this sheeting in desired position upon the mattress.

The infant is laid upon the sheeting 20 and under the cover portion 9-10, whereupon the sections 9-10 are fastened together by means of the hookless fastener and the auxiliary fastener 18. The bottom flap 12 is then tucked under the bottom of the mattress and over the tie member 5, thereby covering and protecting the feet of the infant. Any additional covering that may be desirable or necessary to place upon the bed, may then be placed upon the bed without danger of the same becoming displaced since the cover portion 9-10 is positively retained in desired fixed position with respect to the mattress owing to the retaining action of the tie member 5 and side panels 7. The additional covering is placed on top of the cover sections 9-10 and will remain where placed and cannot be reached by the feet of the infant or be kicked out of place. It will be noted that the weight of the mattress together with that of the infant combine to retain the bed case of this invention in correct position. Also, when tie strings 6 are used, additional security against movement is provided.

It will be noted that the use of the hookless fastener enables the cover portion to be readily parted to place the infant in desired position on the bed or to remove him therefrom. The parting of the cover sections 9-10 by use of the hookless fastener, also enables the ready insertion of the mattress into the case and also enables the ready placing of sheeting upon the mattress and permits the complete airing of the bed in daytime.

Since the case of this invention is open at the bottom as well as the top, it is very easy to tuck the sheet under the bottom and under the top of the mattress, and also gives access to the infant's feet as for the purpose of placing a hot water bag thereon. Since the case is open at its top and bottom, the same may be very readily laundered when desired. As the tie member or subsheet 5 underlies the mattress 3, the infant cannot wet the same and therefore the case may be used at long intervals without laundering.

It is not necessary that the tie member or subsheet 5 should underlie the entire mattress. Thus in Fig. 7, the tie member is illustrated as consisting of transverse strips 5' which interconnect the lower edges of the side panels 7 at the head and foot ends of these panels.

It will be apparent that other fastening means such as hooks, locks, ties and etc. may be used in lieu of the hookless fastener, but such other fastening means would not be as easy to operate as the hookless fastener, nor would they prevent the infant from sticking his fingers outwardly through the line of fastening of cover sections 9-10.

As many changes could be made in the

above construction and many apparently widely different embodiments of this invention could be made without departing from the scope thereof, it is intended that all matter contained in the above description or shown in the accompanying drawing shall be interpreted as illustrative and not in a limiting sense.

What is claimed is:—

1. A bed covering adapted to receive the bed mattress therewith comprising, a tie member of sheeting material arranged to extend under and completely across the mattress, side panels attached respectively at their lower edges to the respective side edges of said tie member and extending upwardly at the sides of the mattress, and a cover portion adapted to overlie the mattress, said cover portion having its respective side edges attached to the respective upper edges of said side panels, said side panels being of greater height than the thickness of the mattress to provide a space between said cover portion and the mattress for receiving a person and sheeting, said cover portion having a flap at its bottom end extending beyond the foot ends of said side panels and adapted to be tucked around and under the bottom of the mattress, so that the free end portion of said flap is frictionally confined between the under surface of the mattress and said tie member.

2. A bed covering adapted to receive the bed mattress therewith comprising, a sheet tie member arranged to extend under and completely across the mattress, side panels extending along a portion of the length of said tie member and being attached respectively at their lower edges to the respective side edges of said tie member and extending upwardly at the sides of the mattress, and a cover portion adapted to overlie the mattress, said cover portion having its respective side edges attached to the respective upper edges of said side panels, said side panels being of greater height than the thickness of the mattress to provide a space between said cover portion and the mattress for receiving a person and sheeting, said cover portion having an opening at its center arranged to be closed when desired, and a flap at its bottom end adapted to be tucked around the foot end and under the bottom of the mattress, and fastener means having parts secured to the marginal portions of said opening for effecting the closing of said opening.

3. A bed covering adapted to receive the bed mattress therewith comprising, a sheet tie member arranged to extend under and completely across the mattress, side panels attached respectively at their lower edges to the respective side edges of said tie member, said side panels being adapted to extend lengthwise from the bottom end of the mat-

tress toward the top end thereof, but terminating short of such top end, and a cover portion adapted to overlie the mattress, said cover portion having its respective side edges attached to the respective upper edges of said side panels, said cover portion having a flap projecting beyond the bottom end of said side panels for wrapping around and under the bottom end of said mattress so that the free end portion of said flap is frictionally held between said tie member and the under surface of the mattress.

4. A bed covering adapted to rest upon the bed spring and to receive the bed mattress therewith comprising, a subsheet arranged to overlie the bed spring and to underlie the mattress, side panels attached respectively at their lower edges to the respective side edges of said subsheet, said side panels being disposed to extend lengthwise from the foot end of the mattress toward the head thereof and terminating short of such head end, whereby a portion of the subsheet projects beyond the head ends of said side panels, a cover portion sewn at its side edges to the upper edges of said side panels and being arranged to overlie the mattress, said cover portion extending the full length of said side panels and having a foot flap projecting beyond the foot ends of said panels, said cover portion consisting of two sections having overlapping edge portions at the center of the cover portion, the overlapping edge portions of said sections being sewn together in the foot flap part of said cover portion, and fastening means for connecting at will the overlapping edge portions of said sections extending above said subsheet.

5. A bed covering adapted to rest upon the bed spring and to receive the bed mattress therewith comprising, a subsheet arranged to overlie the bed spring and to underlie the mattress, tie strings attached to the corners of said subsheet for tying the same to the bed spring, side panels attached respectively at their lower edges to the respective side edges of said subsheet, said side panels being disposed to extend lengthwise from the foot end of the mattress toward the head thereof and terminating short of such head end, whereby a portion of the subsheet projects beyond the head ends of said side panels, a cover portion sewn at its side edges to the upper edges of said side panels and being arranged to overlie the mattress, said cover portion extending the full length of said side panels and having a foot flap projecting beyond the foot ends of said panels for substantially the same distance that the subsheet projects beyond the head ends of said side panels, said cover portion consisting of two sections having overlapping edge portions at the center of the cover portion, the overlapping edge portions of said sections being

sewn together in the foot flap part of said cover portion, and fastening means for connecting at will the overlapping edge portions of said sections extending above said sub-sheet.

5 In testimony, that I claim the invention set forth above I have hereunto set my hand this 21st day of November, 1930.
